UNITED STATES PATENT OFFICE.

DAVID T. MAY, OF NEW YORK, N. Y., ASSIGNOR TO WESTERN ELECTRIC COMPANY,
INCORPORATED, OF NEW YORK, N. Y., A CORPORATION OF NEW YORK.

HIGH-POTENTIAL CONDENSER.

1,307,507.

Specification of Letters Patent. Patented June 24, 1919.

Application filed November 3, 1917. Serial No. 200,077.

To all whom it may concern:

Be it known that I, DAVID T. MAY, a citizen of the United States, residing at New York, in the county of New York and State 5 of New York, have invented certain new and useful Improvements in High-Potential Condensers, of which the following is a full, clear, concise, and exact description.

This invention relates to high potential 10 condensers.

It is well known that in condensers in which the plates of opposite polarity are separated by a dielectric, the electric density, and therefore the electric pressure, is greatest 15 at the edges of the plates or coatings. The dielectric stress therefore concentrates at these edges, although at other points between the plates the stress may be nearly uniform. This concentration of the electric 20 pressure is evidenced by minute discharges or streamers that pass from the coatings to the dielectric, which discharges may be considered to be the charge and discharge currents of elementary condensers 25 composed of the metallic coatings and the partially conducting surfaces of the dielectric. This playing of the streamers over the surface of the dielectric causes local heating in the latter, due to its poor conductivity, 30 thereby subjecting it to additional stresses. By reason of the concentration of the stress, condensers made of glass, porcelain or other materials and constructed after the manner of Leyden jars, almost always break down 35 at points which are not covered by the metallic coatings or plates and which are near the edges of the plates.

The object of this invention is to relieve 40 this concentration of the stress near the edges of the plates so as to eliminate all danger of the dielectric becoming heated and being punctured. This is accomplished by attaching to the condenser near the points of the stress concentration, metallic pieces 45 or caps which are separated from the edges of the main metallic coating by air gaps of suitable dimensions. This relieves the stress concentration since sparks will pass from the main coatings to the additional metallic 50 pieces, thereby dissipating the electrical energy which would otherwise be evidenced by the streamers over the dielectric. Stress due to local heating will also be avoided by this arrangement on account of the good heat

conductivity of the additional metallic 55 pieces.

This invention will be better understood by reference to the accompanying drawings, in which Figure 1 shows one form of this invention, in which metallic caps are employed to accomplish the objects above set forth; and Fig. 2 shows a modification thereof.

In Fig. 1 is shown a condenser of the Leyden jar type having an inner metallic 65 plate 5 and an outer plate 6 with a dielectric 7 therebetween, which extends for some distance beyond the upper edges 8, 8' of the plates. Extending over the edges 8, 8' of the plates are two metallic caps 9, 9' which 70 are suitably attached to the dielectric but are electrically separated from the plates by the air gaps 10, 10' and 11, 11', the latter pair being the greater. When a condenser equipped with these caps is connected to a 75 source of high potential, it is found that the streamers no longer play over the surfaces of the dielectric but that sparks pass across the gaps 10, 10'. In this way, the stress at the edges of the plates 5 and 6 is 80 considerably relieved, and the interposition of the air gaps 10, 10' in the path of the current cuts it down to a point where streamers are not produced to an injurious extent at the edges 12, 12' of the caps. If 85 it is desired, a plurality of caps may be employed, each one being separated from the preceding one by air gaps of suitable dimensions. Herein an additional pair of caps 15, 15' is shown to which sparks may pass 90 if the stress at the edges 12, 12' becomes sufficiently large for a discharge to occur across the air gaps 16, 16'. It is preferable that the gaps 10, 10' should be smaller than the gaps 11, 11', because sparking occurring 95 across the shorter pair of gaps will be to those portions of the metallic caps from which the heat may be radiated away most readily without injuring the dielectric.

In the modification shown in Fig. 2, instead of the metallic caps of Fig. 1, metallic rings 20, 20' are shown sprung against the walls of the jar or otherwise suitably connected thereto. Each of these rings carries a plurality of wire pieces 21, 21' (only 100 one visible for the ring 20'), which form air gaps 23, 23' with the metallic plates 5 and 6. As may be understood from the explanation 105

given with reference to Fig. 1, harmless 5
sparking will occur across gaps 23, 23' on
charging up the condenser to a high potential,
thereby preventing the formation of
injurious streamers. If desired, a plurality
of pairs of metallic rings may be employed
whereby additional spark gaps will be pro-
vided. Herein two additional pairs 25, 25'
and 26, 26' are shown, thereby forming the
spark gaps 28, 28', 29, 29'. Any tendency
for the production of the streamers, due to
stress concentration adjacent to rings 20, 20',
is avoided since the energy will be dissipated
by sparking to pieces 30, 30'. Simi-
larly, sparking across gaps 29, 29' will pre-
vent streamers being formed due to stress
concentration adjacent to rings 25, 25'.

This invention is not limited to the two
modifications above described, as it is evi-
dent to one skilled in the art that it may be
embodied in various other forms without de-
parting in any wise from the spirit of this
invention as set forth in the appended
claims.

25 What is claimed is:

1. The combination with a high potential
condenser comprising a dielectric having
conducting plates on opposite sides thereof,
of means including spark gaps perpendicular
30 to said plates whereby injurious streamers
are prevented from playing over the sur-
face of said dielectric.

2. The combination with a high potential
condenser comprising a dielectric having
35 portions of its opposite sides covered by
conducting plates, of means including spark
gaps perpendicular to said plates whereby
the electrical stress concentration at the
edges of the conducting plates is relieved
40 without injuring said dielectric.

3. A high potential condenser comprising
a dielectric having a portion of its opposite
45 sides covered by conducting plates, and ad-
ditional conducting pieces adjacent to the
edges of said conducting plates but out of
alinement therewith and electrically sepa-
rated therefrom to provide air gaps perpen-
50 dicular to said first plates, whereby the elec-
trical stress concentration at the edges of
said conducting plates may be diminished.

4. A high potential condenser comprising
a dielectric having the major portions of its
opposite sides covered by metallic coatings
and an additional metallic conductor on one
55 side of said dielectric and adjacent to the
metallic coating on said side but out of
alinement therewith, being electrically sepa-

rated from the edges thereof by an air gap
whereby the undesired electrical stress con-
centration may be diminished.

5. A high potential condenser comprising
a dielectric having the major portions of its
opposite sides covered by metallic coatings,
and an additional metallic conductor on one
65 side of said dielectric, a portion of said con-
ductor being bent away from said dielectric
so as to extend over the upper edges of the
dielectric coating whereby the concentration
of the electrical stress at the upper edges of
70 the dielectric coating may be diminished.

6. A high potential condenser comprising
a dielectric having the major portions of its
opposite sides covered by metallic coatings,
and an additional metallic conductor on
each side of said dielectric, a portion of each
75 of said conductors being attached to said
dielectric, with another portion adjacent to
the upper edges of its respective coating be-
ing bent away from said dielectric whereby
the undesirable electrical stress concentra-
80 tion may be diminished.

7. A high potential condenser comprising
a dielectric having the major portions of its
opposite sides covered by metallic coatings,
and a plurality of metallic conductors on
each side of said dielectric, a portion of each
85 conductor being attached to said dielectric
and that portion of each conductor nearest
the upper edges of the metallic coating on
its side of the dielectric being electrically
90 separated from the dielectric immediately
adjacent thereto by an air space whereby the
undesirable electrical stress concentration
may be avoided.

8. A high potential condenser comprising
a dielectric having the major portions of its
opposite sides covered by metallic coatings,
and a metallic cap attached to the exposed
95 part of said dielectric and extending over
the edges of each of said metallic coatings.

9. A high potential condenser comprising
a dielectric having the major portions of
100 its opposite sides covered by metallic coat-
ings, a metallic cap attached to the exposed
part of said dielectric and extending over
the edges of each of said metallic coatings,
and a second metallic cap attached to said
105 dielectric and extending over the upper
edges of said first cap.

In witness whereof, I hereunto subscribe
my name this 30th day of October A. D.,
1917.

DAVID T. MAY.
